(57) **CLAIM**

The ornamental design for a solar lamp, as shown and described.

DESCRIPTION

FIG. 1 is a perspective view of a first embodiment of a solar lamp showing my new design;

FIG. 2 is another perspective view thereof;

FIG. 3 is a front view thereof.

FIG. 4 is a back view thereof.

FIG. 5 is a left view thereof.

FIG. 6 is a right view thereof.

FIG. 7 is a top view thereof.

FIG. 8 is a bottom view thereof.

FIG. 9 is a perspective view of a first embodiment, shown in an alternate state;

FIG. 10 is a perspective view of a second embodiment of a solar lamp;

FIG. 11 is another perspective view thereof;

FIG. 12 is a front view thereof.

FIG. 13 is a back view thereof.

FIG. 14 is a left view thereof.

FIG. 15 is a right view thereof.

FIG. 16 is a top view thereof; and,

FIG. 17 is a bottom view thereof.

The broken lines in the drawings illustrate portions of the solar lamp that form no part of the claimed design.
